Patented Mar. 7, 1972

223,067

ELECTRIC HAIR DRYER BONNET

Norman A. Steinkamp, Chicago Heights, Ill., assignor to
Sunbeam Corporation, Chicago, Ill.

Filed July 6, 1970, Ser. No. 23,840

Term of patent 14 years

Int. Cl. D28—03

U.S. Cl. D86—10

Fig. 1.

Fig. 2.

Fig. 3.

FIG. 1 is a perspective view of an electric hair dryer bonnet showing my new design;

FIG. 2 is a front elevation thereof;

FIG. 3 is a side elevation thereof;

FIG. 4 is a top plan view thereof; and

FIG. 5 is a rear elevation thereof.

I claim:

The ornamental design for an electric hair dryer bonnet, as shown.
